P. I. LANGLYKKE

VALVE RAISING DEVICE

Filed Feb. 6, 1923

Inventor:
PETER I. LANGLYKKE

Dr. Foreé Bain & Hinckle

UNITED STATES PATENT OFFICE.

PETER I. LANGLYKKE, OF CHICAGO, ILLINOIS, ASSIGNEE TO ANTNA MACHINE & MFG. CO., OF CHICAGO, ILLINOIS, A PARTNERSHIP COMPOSED OF PHILIP B. LUTHER AND PETER I. LANGLYKKE.

VALVE-RAISING DEVICE.

Application filed February 3, 1923. Serial No. 317,189.

To all whom it may concern:

Be it known that I, PETER I. LANGLYKKE, a citizen of the United States, residing at Chicago, in the county of Cook and State 5 of Illinois, have invented certain new and useful Improvements in Valve-Raising Devices, of which the following is a specification.

This invention relates to improvements in 10 devices for compressing springs on valve stems to conveniently separate the spring and valve structure.

Internal combustion engines are usually provided with spring-pressed poppet 15 valves.

In such structures an open coiled spring surrounds the valve stem with one end bearing against a relatively stationary part of the engine frame and the other end of the 20 spring bearing against a removable abutment carried by the valve stem, such as a washer, pin or similar device. Usually the movable abutment cannot be removed from the stem while the tension of the spring is 25 applied thereto and the valve cannot be removed from its casing so long as it is biased by the spring.

Preliminarily, therefore, to removing the 30 valve the spring must be released and disconnected from the valve stem and, to facilitate such operation, the spring should be further compressed so that its end, that normally bears against the removable abutment provided on the valve stem, is moved 35 away from the abutment whereupon the abutment may be conveniently and easily removed from the stem and the valve taken from its valve cage.

I have provided a convenient tool for 40 accomplishing the aforesaid result and which will hold the spring compressed to any extent required to facilitate subsequent operations.

In the drawings:—

Fig. 1 shows a plan view of the tool.

Fig. 2 is a side elevation thereof.

Fig. 3 is a substantially central longitudinal section.

Fig. 4 is a cross section taken on line 4—4 of Fig. 3.

In all the views the same reference characters indicate corresponding parts.

The tool consists of two like members 5

and 6 of uniform thickness throughout pivoted together at 7. These members, for 55 economical reasons, are, preferably, punched from and formed up of sheet metal, one being the substantial duplicate of the other; they therefore possess great strength proportional to their weight and are more 60 convenient in use.

Each member is provided with a notched head 8 and 9, respectively. The notch 10 in member 5 is preferably V-shape to surround the stem and the notch 11 may be 65 larger to encompass the stem near the spring or near the relatively fixed abutment.

Each major member 5 and 6 is provided with two ears 12 and 13. The ears 12 are each offset, as plainly shown in Figs. 3 and 70 4 at 14, so that the notches 9 and 10 and the heads 8 and 9 will register.

The member 6 is perforated for the pivoted spring pressed latch bar 15. The bar 75 is pivoted on the pin 16 and is provided with teeth 17 that engage an edge 18 of a slot 19 in the member 5.

A spring 20 having an end 21 passes under the pin 16 and an end 22 which contacts the rear edge of the bar to yieldingly hold 80 the latch-bar in position shown in Fig. 3.

To use the tool the head 9 is slipped under the abutment carried by the valve rod and should rest upon a fixed abutment while the head 8 should be placed directly under 85 the end of the spring and above the removable abutment carried by the valve rod.

When pressure is applied to the members 5 and 6, the heads 8 and 9 are separated and the valve spring is compressed and 90 moved away from the abutment on the valve stem which may now be removed to release the spring when the latter is disengaged by the instrument.

The latch-bar 15 holds the heads 8 and 9 separated so that a workman may use both 95 of his hands in removing the valve.

The portion 23 of the heads 8 and 9 immediately surrounding the respective notches 10 and 11 is countersunk to bring 100 these portions more nearly parallel. This leaves a bead 24 partly surrounding the notches which renders this portion of the head stronger than if this part were left flat.

To cheapen the cost of production the 105

members 5 and 6 are substantial duplicates of each other, one being the ectype of the other. They are punched of sheet metal, by the same punch and die and are trans-
5 versely curved to lend strength and ri-
gidity by the same forming tool. The ears
12 and 13 which form the pivoting mem-
bers with the pin 7 are offset as at 14 so
as to bring the heads 8 and 9 and their
10 notches in register, as shown in Fig. 4,
and the ear 13 of each member lies between
the ears 12 and 13 of the associate member,
as shown in Fig. 4. The ears 12 and 13
15 of each member by this arrangement may
be the same distance apart.

The members 5 and 6 are transversely curved throughout to lend strength and to improve their appearance.

The effective operating part of the latch
20 bar 15 is wholly within the curved portion
of the handles and the spring 20 lies within
in the concave portion of one of said han-
dles or members.

The inner confronting edges of the mem-
25 bers 5 and 6 between the pivotal point and
the end of the heads 8 and 9 are substan-
tially parallel on two straight lines. This
produces a structure of maximum strength
30 and a continuous wedge shape outline from
end to end when the members are in the
positions shown in Fig. 2.

Having described my invention what I
claim as new and desire to secure by Let-
ters Patent, is:—

35 1. A tool of the character described com-
prising two substantially duplicate mem-
bers, transversely curved in cross section
providing confronting concave surfaces,
and hinged together; a widened notched
40 head on like ends of each member provid-
ing a pair of rigid prongs, one on each side
of its notch; a notched latch-bar pivoted
to one member and extending thru a per-
foration in the other member, the wall of
45 said perforation cooperating with said
notches to hold the jaws separated a pre-
determined distance and a spring extend-
ing from the member in which said latch
bar is pivoted to said bar and partly con-

tained in the concave portion of said mem-
ber to actuate said latch bar.

2. A tool of the character described com-
prising two substantially duplicate mem-
bers, of uniform thickness, each member
having a pair of hinge ears containing reg-
istering perforations, like ears of said mem-
bers being laterally off-set to cause register
55 of the respective heads; a pin passing thru
the four ears to hinge the members to-
gether, said members each having a head
containing a notch and said notches brought
into alignment by the off-set hinge ears.

3. A tool of the character described com-
prising two substantially duplicate mem-
bers each of uniform thickness and trans-
versely curved throughout, each member
having a pair of hinge ears containing reg-
istering perforations, a like ear of each pair
of ears being laterally displaced and the
ears of the members being equally spaced,
60 with one ear of one member between the
pair of ears of the other member to bring
the members into transverse alignment; a
pin passing through said four ears to hinge
the members together and a latch to hold
75 the members separated.

4. A tool of the character described com-
prising two substantially duplicate mem-
bers each of uniform thickness and trans-
versely curved to produce a transversely
arched formation from the head thereof
80 to its further end; a widened notched head
on one end of each member, each member
providing a pair of fixed rigid prongs, one
85 on each side of its notch and the edges of
the prongs bounding the notches located
at an angle from the outlines of the mem-
ber to form a spring seat; a pair of hinge
ears extending inwardly from each member,
90 one ear of each pair located between the
pair of the other member; a pin extending
thru said four ears to hinge the mem-
bers together and a spring pressed latch
to hold the heads separated.

In testimony whereof I hereunto sub-
95 scribe my name.

PETER I. LANGLYKKE.
